UNITED STATES PATENT OFFICE

HENRY E. VAN DERHOEF, OF ROCHESTER, NEW YORK, ASSIGNOR TO EASTMAN KODAK COMPANY, OF ROCHESTER, NEW YORK, A CORPORATION OF NEW YORK

HOPPER MOUNT FOR ROLL COATING MACHINES

Application filed November 5, 1930. Serial No. 493,566.

My invention relates to apparatus for the treatment of liquids or plastic materials, and more particularly to apparatus for the making of sheets or films from viscose compositions known in the art as "dope."

In coating thin layers on a support or base, or for producing a film of material of substantially constant thickness, much difficulty has been met with, due to the fact that vibrations arising from numerous causes are transmitted to the dope spreading device or hopper through the machine frame, drive casing, etc., which cause cross lines in the dope as it is being deposited on the dope receiving surface. This is especially true while running the machine on thin stock at a high rate of speed. Under this condition vibrations become more numerous and of greater amplitude and those of different frequencies intercepting one another are additive to form exaggerated points or beats of vibration. The effect of these vibrations is to cause intermittent flow of dope from the hopper thus forming bands or ridges of various thickness.

Investigation shows that these harmful vibrations come from three main sources, first the machine drive, second, moving air in the circulation system and, third, vibrations transmitted through the walls and floor of the building from other machinery.

Vibrations coming under one and three may be materially reduced by installing quiet drives and properly cushioning various parts of the machines, but moving air columns in the wheel casing and dryer casing cause certain agitations which create violent vibrations in the casing imparting this same motion to all light parts of the machine, and a tremor throughout the entire framework, and it has been found impractical to eliminate the source of these vibrations.

It is an object of my invention to provide a machine for the manufacture of sheets or film in which the effect of the above-mentioned vibrations is materially reduced so that sheets or films of substantially uniform thickness are obtainable.

Another object of my invention is the provision of film making apparatus in which

vibrations in the dope receiving surface are duplicated in the dope spreading device or hopper.

In film making apparatus of the rotary drum type, the heaviest individual member is the drum and its shaft and due to its great weight it is slow to respond to or be affected by vibrations and it is an object of my invention to provide such apparatus in which the dope hopper is supported by the rotary drum or its associated shaft whereby the hopper receives only the diminished vibrations transmitted by the heavy drum and shaft.

Another object of my invention is to provide a hopper supported entirely upon the shaft or axle of the rotary drum. Other objects and advantages of my invention will be apparent from the following description when read in connection with the accompanying drawings in which all the views are more or less diagrammatic.

Figure 1 is a side elevation showing a general application of my invention.

Figure 2 is a detailed view of a pendulum mount for the hopper with parts broken away.

Figure 3 is an end view partly in section of Fig. 2 illustrating an assembly of the apparatus.

Figure 4 shows my invention applied to film apparatus of the endless belt type.

Like reference characters represent like parts in all the views.

In the drawings, the base 10 supports the bearings 11 for the shaft 12 of a wheel or rotary drum 13, the cylindrical peripheral facing 14 of the drum 13 moves during rotation in the direction of the arrow 15 from a dope supplying hopper 16 to the film stripping rollers 17.

The hopper 16 is preferably of the usual type having walls 18 and 19 which are adjustable for varying the thickness of the layer of material being flowed upon the drum face 14.

All of these details are well known in the art and further explanation is unnecessary.

As illustrated in Fig. 4, the dope receiving surface 14' comprises an endless belt carried on the drums 13 and 13' in a well known manner and the dope is applied by the hopper 16 at a point where the endless belt 14' is in con-

tact with the drum 13. From this it is obvious that my improved hopper mount is equally applicable to the endless belt type of apparatus and its advantages will be apparent from the following description.

The frame supporting the hopper 16 comprises the arms 20 pivoted in bearing relation on the drum shaft 12 between the drum 13 and the bearings 11. Lengthwise movement of the arm 20 on the shaft 12 is prevented by the collars or sleeves 21 and 22.

The drum 13 is firmly secured to the shaft 12 in any suitable manner to form an integral mass, which, due to its great weight is not materially affected by exterior vibrations. The portions of the shaft 12 extending from the drum 13 may be considered as trunnions and for convenience will hereinafter be referred to as such from time to time.

20 The hopper 16 and its supporting arms 20 must be stabilized in order to remain in the position illustrated and this may be accomplished by a pendulum 23 or a linkage 24 and 25 to some stationary support as the base 10.

25 As shown in Figs. 1, 2 and 3, the pendulum 23 is rigidly connected with the hopper supporting arm 20 and its mass may be adjusted by addition or removal of the weights 26.

30 The arms 20 and pendulum 23 are free to rotate on the trunnions 12 and due to the greater weight of the pendulum 23 the hopper 16 will be held in the upright position illustrated.

35 The possible movement of the pendulum 23 is preferably limited so that it will not swing through any considerable angle, although slight movement, of course, must be permitted. One method of limiting such movement is shown in Fig. 3 as comprising a stop or lug 27 mounted on or secured to the base 10 which is adapted to project between the screws 28 carried by a suitable support 29 mounted on the pendulum 23 in any desired manner.

40 While I have shown and described one embodiment of my invention, I do not intend to be limited thereto as modifications will readily suggest themselves to those skilled in this art without departing from the spirit of my invention or the scope of the claims herein.

45 What I claim as new and desire to secure by Letters Patent of the United States is:

50 1. A film manufacturing apparatus of the rotary drum type including a drum carrying rotatable shaft, a frame supported by said shaft, a dope hopper mounted on said frame, a pendulum associated with said frame for holding it against rotation, fixed bearings for said shaft and stops mounted on said bearings for limiting the swinging of said pendulum.

55 2. A film making machine including a dope depositing device, a dope receiving rotary

drum, a rotatable shaft carrying said drum and a frame pivoted on said shaft and supporting said dope depositing device, said frame being weighted for holding it against rotation.

60 3. In a film making machine, the combination with a rotary drum mounted on a shaft of a frame pivoted on said shaft and weighted to hold the frame stationary and a hopper mounted on said frame in dope spreading relation with said drum.

65 Signed at Rochester, New York, this 30th day of October, 1930.
